INTERNAL-COMBUSTION ENGINE WITH
VARIABLE COMPRESSION RATIO

Oscar E. Rosaen, Detroit, Mich., assignor of one-third to Borge Rosaen and one-third to Nils Rosaen, both of Detroit, Mich.

Application July 25, 1946, Serial No. 686,085

2 Claims. (Cl. 123—48)

1

The present invention relates to internal combustion engines and more specifically to the combustion chambers of such engines.

Among the objects of the invention is an engine provided with combustion chambers which are automatically variable in size in accordance with load conditions.

Another object is hydraulic means for varying the capacity of the combustion chambers and maintaining the movable element or elements during the high pressure periods.

Another object is hydraulic means for the purpose indicated which is controlled in its operation by conditions of pressure in the intake manifold.

Still other objects and advantages will be apparent to those skilled in the art upon reference to the following description and the accompanying drawings in which

Fig. 1 is an end elevation of an internal combustion engine equipped with the present invention.

Fig. 2 is a sectional view on a vertical plane transverse of the engine and passing through one of the cylinders and through the control hydraulic cylinder.

Fig. 3 is a section on line 3—3 of Fig. 2.

Fig. 4 is a diagrammatic view indicating the hydraulic fluid flow.

Fig. 5 is an elevational view of a detail of construction.

Fig. 6 is a section on line 6—6 of Fig. 5.

Fig. 7 is a section on line 7—7 of Fig. 2.

In the drawings, there is shown an internal combustion engine which, with certain exceptions noted below, may be conventional from the tops of the cylinders down. That is, it may have the usual water-jacketed cylinder block 10, crankcase 11, intake and exhaust manifolds 12 and 13, etc.

The engine shown is provided with a conventional drive belt 15, driving the fan 16 and water pump, and the generator 17, and in addition to these accessories, in the present invention, the same belt may be used to drive a hydraulic pump 20.

This latter pump 20 may be any suitable type, reciprocating or rotary but should be capable of delivering an excess of fluid under a sufficiently high pressure.

As indicated in Fig. 4, the pump 20 may take oil from the crankcase 11 or other suitable reservoir of the engine through a conduit 21 and deliver it through a pressure relief valve 22 and conduit 22A to a manifold 23 from which individual conduits 24 lead to the superstructure

2

25 of the engine. From the latter, the oil will be returned through conduit or conduits 26 to the crankcase or reservoir.

Referring now more particularly to Figs. 2 and 5, the engine shown is of the L-head type with the combustion chamber offset from the cylinder 30 and above the valves 31.

The combustion chamber is shown as a short cylinder 32, preferably jacketed as at 32A, and containing a piston 33, and is so located that it extends over a portion of the cylinder 30 and over the valves 31, being cut away as at 33A for valve clearance when it is in its lowest position. The piston 33 may also be provided with a groove or passageway 33B (see Fig. 3) affording communication between the spark plug pocket 30A and the valve pocket when the piston 33 and the lower piston 30B are in the position of their closest approach.

20 The piston 33 is, as shown, hollow and provided with a cover plate 34 held in place by suitable screws, which cover plate is provided with several openings allowing free communication between the interior of the piston and the cylinder space 15 above it. Three or more of such openings serve also for the passage of bolts 36 which extend into the piston and carry springs 36A which, acting between the bolt heads and the plate 34, tend to lift the pistons, these bolts 36 being anchored 30 at their upper ends in a perforated plate 37 topping the cylinder 32.

The plate 34 is also provided with a relatively large central opening to receive a sleeve member 38, shown in Figs. 5 and 6. This member consists of a sleeve of which the mid portion is enlarged as at 32A and provided with a plurality of openings 38B. The enlargement 38A is seated in the underside of plate 34 and held resiliently therein by a suitable spring 38C.

40 The lower end of sleeve 38 is closed by a suitable plug and provides space for the movement of a hollow rod 39 arranged to fit slidably in the sleeve and is normally positioned with its lower end at or below the bottom of sleeve enlargement 45 38A, forming a valve therewith.

The hollow rod 39 extends up through the top plate 37 inlet chamber 40 and outlet chamber 41 and through the cover plate 41B of the latter and is provided at its upper end with an eye or other means for pivotal connection with a link 42. At that portion of the rod within the outlet chamber 41, the rod is provided with openings 41A affording communication between the interior of the rod and the chamber 41. It is preferred to support the rod 39 in a sleeve 39A ex-

tending down through both chambers 40 and 41 and forming a suitable bearing for the rod.

The link 42 connects the rod 39 to a short arm 43 fixed to a shaft 44 extending over the several cylinders and of course carrying as many of the arms 43 as there are cylinders.

The shaft 44 is mounted in suitable bearings and is oscillatable by means of a long arm 45 keyed thereto and linked as at 46, to a piston rod 47 which extends into a cylinder 48 and is connected to a suitable piston 49 therein. Surrounding the rod 47 and acting between the cover plate 52 of the cylinder 48 and tension adjusting nuts 50 carried by the rod is a suitable spring 51.

The cover plate 52 of the cylinder is perforated as at 52A, and the space under the piston 49 is connected through a conduit 53 to the intake manifold 12 of the engine.

In the operation of the invention, assuming the engine to be not running and all oil spaces filled, the spring 51 will have moved the arm 45 up to its extreme upper position. The rod 39 will therefore have moved up and thereby opened communication between the interior of piston 33 and outlet chamber 41 through the rod, so that the springs 36A will have moved the piston 33 to its upper position, thereby increasing the capacity of the combustion chamber.

When the engine is cranked for starting and before oil pressure is built up in the manifold 23, suction in the intake manifold 12 begins to act on piston 49 but the movement of piston 33 is little or none until sufficient oil pressure develops. As soon, however, as the engine begins to operate, the oil pressure in manifold 23 forces the pistons 33 down and positions them in accordance with the intake manifold pressure, and adjusts such positions with changes in the throttle position.

When the engine is running but with the throttle closed to idle position, the lowest pressure exists in the intake manifold and consequently piston 49 and valve number 39 are in their lowest positions. Also, pump 20 is supplying oil to the chamber 40 and top of piston 33.

With these parts in such positions, valve 38-39 is closed and all of the oil delivered by the pump flows through relief valve 22 back to the sump.

When, however, pressure in the manifold increases, piston 49 rises and lifts valve number 39 from its seat thus allowing escape of some of the oil into chamber 41 and also allowing the springs 36A to lift the piston 33. This movement of piston 33 tends to or does close the valve 38-39 again, but the piston 33 has assumed a higher position corresponding with the position of piston 49.

In actual running, the valve 38-39 will seldom, if ever, be entirely closed.

I claim:

1. In an internal combustion engine, a combustion chamber having a movable wall in the form of a hollow piston, a sleeve therein, said sleeve being closed at its inner end and being axially located and provided with openings affording communication between the hollow piston and the interior of said sleeve, a hollow rod slidable in said sleeve and extending to beyond said openings, a pressure chamber adjacent said piston and communicating with the chamber therein, and outlet chamber disposed above said pressure chamber, said hollow rod passing through said chambers and having openings into said outlet chamber, an oil pump actuatable by said engine and adapted to supply oil under pressure to said pressure chamber whereby to move said piston in a direction to decrease the capacity of said combustion chamber and at the same time open the sleeve openings to allow oil to flow through said rod to said outlet chamber, means for positioning said rod whereby to control movement of said piston and means affected by intake manifold pressure to control said positioning means.

2. Superstructure for an internal combustion engine including a cylinder having its lower end partially overlying a working cylinder and providing a combustion chamber therefor, a piston 30 in said first mentioned cylinder, means for supplying oil under pressure to said first mentioned cylinder above said piston, resilient means for resisting the downward movement of said piston and valve means for controlling the outflow of oil 35 from said first mentioned cylinder, said valve means consisting of two cooperating members, one of which is carried by said piston and the other of which is controllably movable axially of the first mentioned cylinder.
